(57) **CLAIM**

The ornamental design for an oven range, as shown and described.

DESCRIPTION

1. Oven range
- 1.1 : Perspective
- 1.2 : Front
- 1.3 : Back
- 1.4 : Left
- 1.5 : Right
- 1.6 : Top
- 1.7 : Bottom
- 1.8 : Perspective
- 1.9 : Front
- 1.10 : Back
- 1.11 : Left
- 1.12 : Right
- 1.13 : Top
- 1.14 : Bottom

The oblique shade lines in Figs. 1.1 and 1.2 depict a translucent surface and those in Figs. 1.8 and 1.9 depict a transparent surface. The transition from a translucent to a transparent surface is achieved by means of a sensor. The

(Continued)

broken lines and the areas within them in the drawings depict portions of the oven range that form no part of the claimed design. Reproductions 1.8 to 1.14 show the door of the oven range in an alternate state of use.

1 Claim, 14 Drawing Sheets
